Primary Examiner — Cynthia Underwood(74) *Attorney, Agent, or Firm* — WPAT, PC; Justin King(57) **CLAIM**

The ornamental design for a wired cable management device, shown and described.

DESCRIPTION

FIG. 1 is a front perspective view of the wired cable management device showing my new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof; and,

FIG. 8 is a back perspective view of the wired cable management device showing my new design.
